UNITED STATES PATENT OFFICE.

RAYMOND H. SULLIVAN, OF ROCHESTER, NEW YORK, ASSIGNOR TO NORTH EAST ELECTRIC COMPANY, OF ROCHESTER, NEW YORK, A CORPORATION OF NEW YORK.

GENERATOR REGULATION.

Application filed December 15, 1922. Serial No. 607,099.

To all whom it may concern:

Be it known that I, RAYMOND H. SULLIVAN, a citizen of the United States, residing at Rochester, in the county of Monroe 5 and State of New York, have invented certain new and useful Improvements in Generator Regulations; and I do hereby declare the following to be a full, clear, and exact description of the invention, such as will 10 enable others skilled in the art to which it apertains to make and use the same.

This invention relates to the regulation of the output of electric generators of the type in which the field-winding, instead of 15 being connected in shunt across the main brushes or terminals of the generator, is connected between one main brush and a third or supplementary brush.

A generator of the third-brush type, when 20 driven at variable speed and connected constantly with a storage-battery, is self-regulating to the extent that its output does not become excessive at any speed. Both voltage 25 and quantity of the output are variable, however, and accordingly additional regulating means are sometimes used with such a generator, such means having usually the form of an electro-magnetic vibratory device by which the circuit through the field- 30 winding is rapidly opened and closed, at a rate depending on the characteristic of the generator output which it is desired to control.

A vibratory regulator for the purpose in 35 question suffers from the difficulty that its contact-points heat and burn away rapidly. For that reason it is customary to connect a resistor in shunt with the contact-members of the regulator, to carry the heavy 40 induced current occurring at each separation of the contacts. Since this resistor affords an alternative path for current through the field-winding, it limits the effectiveness of the regulator if it be of 45 low resistance, while its effectiveness to protect the contacts is slight if it be of high resistance.

The object of the present invention is to 50 produce a system, of the kind just described, in which the contacts of the regulator shall be effectively protected from the burning effect of the interrupted current without reducing the effectiveness of the regulator. This is accomplished by the use of a sec- 55 ond resistor, which is so arranged as to

reduce the electromotive force effective on the field-winding when the contacts of the regulator are open, while not appreciably affecting the field-winding when the contacts are closed.

The invention is more particularly described in connection with the accompanying drawing, which is a diagram of a battery-charging system embodying the invention.

In the illustrated embodiment of the invention the generator 1 has main brushes 2 and 3, and a third or supplementary brush 4. The main brushes are connected with load-conductors 5 and 6. The field-winding 7 is connected, at one end, with the third brush 4, while its other end is connected with the conductor 5 and the main brush 2. A storage-battery 8 is connected across the conductors 5 and 6, and a reverse-current cut out 9, of any ordinary or suitable form, may be interposed in one of the load-conductors, to prevent discharge of the battery when the generator is at rest.

The regulator is or may be of ordinary 80 form, comprising a magnet 10 which is energized by current from the load-conductors. The armature 11 of the regulator cooperates with a fixed contact 12, which is connected, by a wire 13, with the conductor 5. A resistor 14 is connected in shunt with the contacts of the relay.

The apparatus, as so far described, is in accordance with prior practice, and the present invention resides in the use of a 90 second resistor 15 which is connected between the wire 13 and the conductor 6. This resistor has preferably a substantially higher resistance than the resistor 14, and it may be of any ordinary form or mate- 95 rial. It is shown, however, as a lamp having a filament of tungsten or other refractory metal. The resistor 14 may have a resistance sufficiently low to protect the contacts against destructive sparking.

This apparatus operates as follows: So long as the voltage across the load-conductors remain closed, thus affording a path of low 105 resistance for current flowing between the brushes 4 and 5 and through the field-winding. Current also flows through the resistor 15, but this current is so small in amount that it does not substantially affect 110

the operation of the generator. If now the voltage rises above normal, the regulator-contacts are drawn apart, thus opening the circuit through the field-winding, except for the resistor 14. This momentarily weakens the field and cuts down the output of the generator, whereupon the regulator-contacts close again, and this cycle is rapidly repeated so as to maintain the output-voltage of the generator at an average equal to the required amount.

The effect of the resistor 15 during this operation of the regulator is to afford a bypass for a part of the current passing through the resistor 14, when the regulator-contacts are open. In so doing it deprives the field-winding of a part of the current which it would otherwise receive, thus giving the equivalent, so far as the effectiveness of the regulator is concerned, of a higher resistance in the resistor 14.

The use of a metal-filament lamp as the resistor 15, while not essential, is particularly advantageous, owing to the high positive temperature coefficient of resistance of the refractory metal of the filament. This lamp should be of a rating such that when the regulator-contacts are open it will carry the current passing through it at that time without being raised to incandescence. When the regulator-contacts are closed, on the other hand, the increased current through the lamp raises the temperature and the resistance of the filament, and this increase is thereby limited and the loss of energy is minimized. In the same way the intensity of the current which must be broken by the regulator contacts is limited.

It will be apparent that the ultimate effect of the resistor 15 is to permit the regulator, without loss of effectiveness, to operate in conjunction with a smaller resistance at 14 than could otherwise be used, and that this has the effect of diminishing sparking by affording a more effective path for the induced current from the field-winding. This result is to some extent counteracted by the fact that the contacts have to interrupt, in part, the current flowing through

the resistor 15, but since this resistor is non-inductive, interruption of the current through it produces relatively little sparking, and the net result is to substantially improve the operation and increase the life of the contacts.

55

While the absolute and relative resistances of the resistors 14 and 15 may be varied widely, it may be stated that in the case of a generator, of the kind used upon an automobile, having a rating of 12 volts, the resistor 14 may suitably have a resistance of about 5 ohms and the resistor 15 of 12 ohms. A 15 candle-power 12-volt tungsten lamp may be used for the latter, and a lamp of 32 candle-power may also be used as the resistor 14 with good results.

The regulator is shown diagrammatically as connected with the load-conductors in such a manner as to act to maintain a constant voltage in the generator-output, but it will be apparent that it may be arranged, in any well known manner, to control the generator with respect to quantity of output or with respect to some function of quantity and voltage.

75

The invention claimed is:

1. The combination, with an electric generator having main brushes, a third or auxiliary brush and a field-winding of which one terminal is connected to the third brush, a resistor connecting the second terminal of the field-winding with one of the main brushes, and a vibratory regulator arranged to short-circuit said resistor intermittently in accordance with variations in a characteristic of the output of the generator, of a second resistor connecting said second terminal of the field-winding with the other main brush of the generator.

80

2. The combination set forth in claim 1, characterized further by the fact that said second resistor has a high positive temperature coefficient of resistance.

85

3. The combination set forth in claim 1, characterized further by the fact that said second resistor has a substantially higher resistance than the first said resistor.
